SINGLE STATION SHOWER

Harper Landell, Whitemarsh, and Charles F. Molzen,
Philadelphia, Pa., assignors to Speakman Company

Original design application July 26, 1963, Ser. No. 76,216.
Divided and this application Jan. 8, 1964, Ser. No.
78,585

Term of patent 14 years

(Cl. D91—3)

FIGURE 1 is a perspective view of a single station shower embodying our new design;

FIGURE 2 is a front elevational view of the same;
FIGURE 3 is a side elevational view of the same;

FIGURE 4 is a top plan view of the same; and

FIGURE 5 is a cross-sectional view thereof taken on line 5—5 of FIGURE 2.

Portions shown in broken lines are included for illustrative purposes only.

This application is a division of our copending application Serial Number D. 76,216, filed July 26, 1963.

We claim:

The ornamental design for a single station shower, as shown and described.
